RALPH E. NEWTON, OF MILWAUKEE, WISCONSIN.

REINFORCEMENT FOR CONCRETE STRUCTURES.

960,382.

Specification of Letters Patent. Patented June 7, 1910.

Application filed March 21, 1907. Serial No. 363,725.

To all whom it may concern:

Be it known that I, RALPH E. NEWTON, a citizen of the United States, residing at Milwaukee, in the county of Milwaukee and 5 State of Wisconsin, have invented certain new and useful Improvements in Reinforcement for Concrete Structures; and I do hereby declare the following to be a full, clear, and exact description of the invention, 10 such as will enable others skilled in the art to which it appertains to make and use the same.

My invention relates to means for reinforcing concrete structures and is applicable to various kinds of reinforced concrete constructions, whether columns, beams, 15 trusses or the like.

One object is the provision of a reinforcing structure which will be economical to 20 manufacture and ship and easily and speedily applied at the site of the proposed structure.

A further object attained is that any desired combination of grades of material may 25 be used, such as high tension steel for the supporting bars and low tension or soft steel for the connecting straps. Furthermore, the straps are adaptable to any form of bars and the material may be worked up or prepared in the shop instead of in the field, 30 thereby insuring greater accuracy and better workmanship.

Another object is the provision of a continuous strap connecting the bars whereby 35 the use of separate clips or clamps is avoided either for connecting the bars together or for connecting the straps to the bars.

Another object is to construct and arrange 40 the connecting straps to occupy different planes in the concrete structure in which they are embedded with the longitudinal bars and thus to resist strains and stresses therein transversely to the bars.

A still further object is the provision of 45 a strap which is slotted and expanded to receive the bars. The prior art discloses constructions wherein the bars themselves are slotted or punched out to form tongues for supporting or receiving the connecting 50 straps. Such structures are improper, for the reason that the strength of the bars is in direct ratio to their cross sectional area

and by slotting the bar the strength is diminished to that extent.

The structure depends for its strength 55 upon the strength of the bars, rather than upon the strength of the connecting straps, and to cut into the bars is to materially reduce the strength of the structure and in applicant's invention, no effective section is removed either from the band or the bar.

To these and other ends, therefore, my invention consists in certain novel features and combinations of parts, such as will be more fully described hereinafter and particularly pointed out in the claims.

In the accompanying drawings, Figure 1 is a top plan view of a beam or column showing my invention applied thereto; Fig. 2 is a side elevation thereof; Fig. 3 is a 70 detail perspective view of the strap showing one means for receiving the bars; Fig. 4 is a perspective view showing the strap applied as a stirrup for a beam or truss; and Figs. 5 and 6 are enlarged detail top 75 plan and side views showing one manner of splicing or lapping the ends of the bands or straps.

At the outset, it should be understood the invention is not restricted in its application 80 to any particular form of concrete construction, nor is it necessary to have reinforcing bars of any special shape. They may be round, square, or deformed, as preferred. Nor need the structure to which the reinforcement is to be applied be of any special 85 shape or size, the invention being capable of use throughout the entire field of reinforced concrete construction.

Thus (A) (A) indicate the reinforcing 90 bars of any desired shape and size, which preferably extend longitudinally of the structure and impart strength thereto, as many bars being used as is desirable. These bars which are unweakened by slits, perforations, notches or the like, serve in the several structures shown in the drawing as the main tension members.

(B) indicates a transverse spacing and auxiliary strengthening strap or band adapted to connect the bars in any suitable manner, as shown for instance in Figs. 1 and 4. Fig. 4 discloses three methods of applying the band relative to the reinforcing bars,

the band at the left being continuous while the remaining bands are open. These bands are longitudinally slitted, as shown at (1) in Fig. 6, there being either one or more slits as is deemed most desirable. Fig. 3 shows a band having two parallel slits formed therein. By slitting the bands in this manner, the bands at the slitted points are divided into strands (2) (2), which I prefer to expand in the manner shown, whereby to form eyes in or through which the longitudinal bars are received, the strands operating to embrace the bars and securely retain them in the proper spaced relations.

Obviously the size and shape of the structure to which the reinforcement is to be applied must be taken into consideration, and the slitted portions arranged at the proper distances apart.

When the strap or band is to be continuous, as shown in Fig. 1, it is made so that its ends will overlap, the ends being slitted and expanded, as shown, so as to fit over that bar located at the meeting point of the ends of the band, the extreme ends of the band overlapping, as shown at (3) (3), which ends may be riveted to the band, if desired. From an inspection of Fig. 5, it will be seen that the band, at its splicing point, is in effect doubled, the strands overlying each other, as shown, and the bar forms a lock or key to retain the ends together. The expansion of the strands may fit them for use in connection with any preferred form of bars.

Of course, the ends of the band may be riveted together at some point intermediate the bars, if desired.

In Fig. 4, I have shown the strap or band applied as a stirrup to reinforce longitudinally extending bars adapted for floor beams and the like.

When applying the invention to columns or beams, for instance, the longitudinal bars are first set up, after which the straps or bands are slipped over the ends of the bars and moved along to the proper position, the frictional engagement of the straps with the bars being sufficient to retain the former in adjusted position, after which the mold is built up around the skeleton column thus formed and the concrete placed therein.

In the reinforcement of columns and beams as herein shown and described, the transverse spacing straps or bands B are bent to occupy different planes and to resist

strains and stresses in different directions transversely to the bars A.

Having thus fully disclosed my invention, 60 what I claim as new is—

1. In a reinforced concrete structure, the combination with longitudinal bars of transverse spacing straps or bands connecting said bars at intervals and each bent to occupy different planes and to resist strains and stresses in different directions transversely to said bars, the straps or bands being slitted to form strands which are expanded in opposite directions to receive and 70 embrace said bars, substantially as described.

2. In a reinforced concrete structure, the combination of main unweakened tension bars and continuous spacing and auxiliary 75 strengthening straps connecting said bars at intervals and slitted lengthwise at intervals to form strands which are expanded in opposite directions, the strands adjacent to adjoining ends of the bands overlapping one 80 another and the bar passing between the oppositely bent and lapping strands serving as a key to connect such ends, each strap being bent to occupy different planes and to resist strains and stresses in different directions substantially as described.

3. A concrete column comprising a plurality of spaced-apart vertical rods, a plurality of metal bands each having a plurality of angular bends between its ends said 90 angular bends registering with the said vertical rods and at said angular bends each band also having an integrally-formed loop,—the bands being arranged in different horizontal planes with their loops and bends in 95 vertical alignment and the bends and loops at opposite ends of each band encircling the same rod.

4. A concrete column having a plurality of vertical rods embedded therein, flexible 100 metal bands bent around and encircling the group of rods in different horizontal planes and each band having integrally-formed endless loops at each bend through which the vertical rods project and the two endless loops at the end bends of the same band engaging the same vertical rod.

In testimony whereof I affix my signature in presence of two witnesses.

RALPH E. NEWTON.
